STAPLE HAMMER

Robert E. Barclay, Chicago, Ill., assignor to Vail
Manufacturing Company, Chicago, Ill., a cor-
poration of Illinois

Application June 15, 1945, Serial No. 599,553

11 Claims. (Cl. 1—49)

1

The invention relates to a manual implement for feeding and driving staples, tacks, or other fasteners, usually in strip form, and is adapted for operation in the manner of a hammer to drive the staples, tacks, or the like, into wood or other penetrable material.

It is the primary object of this invention to devise, for the purpose mentioned, an implement which is inexpensive, simple, and sturdy in construction and dependable in operation. In accomplishing this end I utilize a minimum of working and moving parts, all of which may be of rugged design. The construction is accordingly light in weight and serviceable over a long period of years.

These and other objects of my invention, as will hereinafter appear, are attainable by a construction of which a certain preferred embodiment is set forth in the accompanying drawings, wherein;

Figure 1 is a side elevation of the implement in its entirety, with the enclosing casing therefor shown in longitudinal section;

Fig. 2 is a horizontal section, taken on line 2—2 of Fig. 1;

Fig. 3 which is a detail in vertical section through the casing, shows the enclosed head end of the implement in side elevation;

Fig. 4 is a central vertical section of the head end of the implement, taken on line 4—4 of Fig. 2;

Fig. 5 is a transverse section taken on line 5—5 of Fig. 4;

Fig. 6 which is a transverse section taken on line 6—6 of Fig. 4 omits from the showing the casing in which the working parts are enclosed; and

Fig. 7 is a view in perspective of the driver head per se.

The present implement comprises a lever swingingly mounted upon a head carried by a hollow handle in which is provided a magazine for holding a supply of staples or other fasteners; it comprises also means for automatically feeding the staples or fasteners into driving position relative to a driver which is connected with the lever, the lever being released by impact when a blow is struck, to advance with high velocity to force each staple or fastener successively into the work. While the invention as illustrated and described is referred to as an implement for driving substantially U-shaped staples, it is to be understood that it may, with slight modification, feed and drive fasteners of other types, such as tacks, brads, nails, or the like. Throughout the spec-

2

ification and claims therefore, the term "staple" is used to indicate broadly all forms of pointed fasteners which may be driven to position by the implement of my invention.

5 I utilize an exterior casing A of channel form which in the handle region is slotted to define a pair of spaced walls 10 and 11, appropriately configured for comfort in handling and use. These walls enclose between them a pair of plates 12 and 13 (see Fig. 5) which are fitted to a bar B constituting a core formed in its upper region with a longitudinal slot 15 defined by walls 16 which are inset from the base of the core. The core plates 12 and 13 extend vertically for the full 15 height of the core and slightly beyond where in-turned flanges 17 are provided to define between them a slot 18. The parts thus far described may be interconnected, some or all of them, by a plurality of fastening elements such as cross 20 pins 19 and screws 20.

In the handle region the casing walls are extended upwardly beyond the core plates and then slightly inwardly to define between them a wide slot which is bordered by shoulders wherein may 25 be seated a closure 25 in the form of a plate which is hinged to the casing top, at 26, toward the head end of the implement. The opposite end of this closure plate is extended to the handle extremity and then downwardly, where it is formed with a 30 nose 28 adapted to engage with a recess in the handle end, after the manner of a detent, so as to hold the closure plate releasably in place.

The staples s to be used with the present implement are desirably arranged in a row, releasably 35 connected together and adapted to straddle the core walls 16, legs down. A channeled follower block 30 is adapted to ride along upon the core walls behind the endmost staple, a flat spring 31 being connected to the follower whereby to maintain it with tension against the staples. In some 40 such way the staples may be fed forwardly toward the head end of the implement where they are driven, one at a time, into the work.

The mechanism thus far described is generally 45 similar to that which is set forth in my pending application, Serial No. 491,441, filed June 19, 1943, granted Dec. 16, 1947, as Letters Patent of the United States No. 2,432,853. From this point on the description is concerned with features of construction which I regard as new and special to 50 this invention.

The core bar which continues for the major portion of the length of the implement terminates at its forward end in an upstanding and 55 outstanding head wall 35 adapted to abut end

flanges 36 of a head unit C which carries the operating mechanism. As by means of screws 37 the head unit is secured fixedly to the head wall of the core bar B which is the back bone of the handle. The head unit comprises a lower block 40 with sides partly inset (see Fig. 6) to align with the core walls 16 whereby to form a staple guideway in continuation therewith; a shorter upper block 41 having a forwardly extending ledge 42 adjacent its bottom, the rear end of this block terminating at a point remote from the abutment wall 35 of the core bar; and a pair of interconnecting side plates 43 fitted alongside the upper and lower blocks, and extending rearwardly of the former to define between them a chamber 44 only open at the top. These plates at their rear ends carry the out-turned flanges 36 whereby connection is made to the core bar. The spring 31 which is extended forwardly through a slot 45 in the abutment wall of the core bar, is coiled within the chamber 44 around a cross bolt 46 to which it is connected.

At the end of the head unit is affixed an anvil plate 50 formed on its inner face with a vertical guideway 51 through which the staples s are successively fed preliminary to being driven, feet first, into the work. The anvil plate is preferably formed integral with the upper block 41. The anvil guideway lies at the forward end of the core guideway through which the staples are advanced longitudinally of the handle. A driver 52 is provided to move in a straight line through the vertical guideway from a top position just above the endmost staple (see Fig. 4) to a bottom position (see Fig. 3) wherein the staple is ejected from the slot. This driver which may be in the form of a flat steel blade is fitted at its upper end with a weighted head D to which it may be connected as by means of a screw 55 passing through a lock washer 56 and an opening in the driver blade to enter a threaded socket 57 in a body 58 which, as shown best in Fig. 7, is formed with a pair of forwardly extending flanges 59, one lying adjacent each narrow edge of the driver blade. Extending outwardly from the flanges is a pair of aligned trunnions 60, and above the flanges, extending rearwardly thereof, is carried a weighted top 61 to augment the power of the driver when operated. The upper end of the driver blade desirably abuts the top so as to receive thrust therefrom.

The driver is pivotally and slidably connected with a lever E, which, as shown, is formed of duplex arms 65 interconnected by a pivot pin 66 which is extended through the upper block 41 and side plates 43. The duplex arms of the lever are further interconnected by a pin 67 near their free ends, thin pin being disposed below the overhanging weighted top of the driver head and above the ledge 42 of the block 41. Each of the lever arms is formed with a slot 68 elongated in a direction away from the lever axis and located in the region of its free end to receive one of the trunnions 60. In its oscillations, the lever will transmit vertical reciprocatory movements to the driver through the sliding connection thus afforded by the slots 68 wherein the trunnions 60 are slidably fitted.

The lever is normally sustained in an upward position, counter to gravity, as by means of a compression spring 70 whose upper end is engaged with the cross pin 67 between the lever arms. The lower end of this spring may be seated within a socket 71 that is provided on the

forward ledge 42. The spring will compress, as required, when the lever is swung downwardly (see Fig. 3), but after impact with the work will expand to restore the lever E to its upper position, the driver also in this movement being raised to its initial position ready for the next operation.

I employ with the present staple driver and lever a striker F having a nose 75 joined to the ends of duplex rocker arms 76 which are pivoted to oscillate upon a cross pin 77 which extends transversely through the lower block 40 of the head unit at a point which is relatively close to its lower edge. The striker nose normally is projected slightly forwardly and below the head unit to occupy a pilot position in which it will engage the work in advance of the head unit itself when the staple lever is operated. The rocker arms, at their rearward ends, make connections 78 with the lower ends of a pair of links 79 whose upper ends are pivotally joined at 80 to the lever arms 65 at a point medially of their length. With each operation, the striker whose normal position is as indicated in Fig. 1, will, upon impact with the work, be rocked upwardly at its forward end, thereby exerting a down pull through the link connections to swing the lever downwardly. The driving motion thus imparted to the hammer is initiated by the force transmitted from the yielding striker, and is at once supplemented by the force of momentum consequent upon unyielding impact of the head unit with the work. Each such operation produces a powerful down thrust upon the driver which acts to displace the endmost staple and drive it into the work. The end of an operative cycle is reached when the lever, in response to tension of the spring 70, is raised upwardly to its limit against a stop plate 85 formed with a longitudinal slot 86 through which is extended a locking screw 87 which secures it in a desired position of adjustment.

The hammer operating mechanism herein described is advantageous in various respects. All parts are in line with the center of the implement or duplicated on opposite sides thereof in an exactly balanced relationship so as to attain the maximum efficiency in movement. The power force is transmitted through a duplex lever F of the first class (the striker) in link connection with a duplex lever E of the third class. The fulcrum point of the striker and/or the power point of the lever may obviously be located within fairly wide limits relative to the lengths of these two levers, according to whatever movement ratio is found to be most satisfactory for a particular purpose. Regardless of the exact proportions and sizes which may be selected, the mechanism remains compact and sturdy, and may be depended upon to perform satisfactorily over an extended period of service.

It will be noted that the present staple hammer comprises a core bar on one end of which is formed a head wall 35 that extends both laterally and upwardly; also in abutting relation with this head wall are flanges 36 out-turned from the ends of side plates between which are mounted upper and lower blocks forming the head end of the implement. The side plates, by reason of the screws 20, pivot pins 66 and 77, and cross bolt 46, interconnect the two head blocks immovably. This head unit is applicable to or detachable from the end of the core bar, thereby promoting convenience in manufacture, assembly,

and possible replacement or repair. In such a construction the outer casing A which serves primarily to enclose the working parts, may be removed whenever occasion may require without disturbing any of the operating parts which in such circumstances are then exposed for such attention as may be necessary.

I claim:

1. A stapling implement comprising a reciprocal staple driver, a guideway for confining the driver movements to a straight line, a striker movable by impact with the work, an oscillatable lever in pivotal sliding connection with the driver, a link connection between the striker and lever, and a handle having a head furnishing a mounting for the driver guideway and for the striker and the lever.

2. A stapling implement comprising a lever, a striker movable by impact with the work, means connecting the striker to the lever, a handle whereon is formed a guideway for processional advance of staples therethrough, a head at one end of the handle comprising two parts separated to provide between them a continuation of the staple guideway, means connecting the two head parts as a unit, and means providing pivotal mountings for the lever and the striker on the head.

3. A stapling implement comprising a head, a staple driver positioned in the head and movable upwardly and downwardly, a lever of the third class fulcrumed in the head and pivotally connected with the staple driver and arranged to swing upwardly and downwardly, a work striker pivoted intermediate of its ends in the head and having a nose movable upwardly by impact with the work, and a link pivotally connected with the said lever and with the striker in rear of the pivot thereof whereby the lever and the driver will be moved downwardly by said impact of the striker with the work.

4. A stapling implement comprising a head, a staple driver positioned in the head and movable upwardly and downwardly, a lever of the third class fulcrumed in the head and pivotally connected with the staple driver and arranged to swing upwardly and downwardly, a work striker pivoted intermediate of its ends in the head and having a nose movable upwardly by impact with the work, a link pivotally connected with the said lever and with the striker in rear of the pivot thereof whereby the lever and the driver will be moved downwardly by said impact of the striker with the work, and a spring acting to restore the driver, the lever and the work striker to their initial positions.

5. A stapling implement comprising a head, a reciprocal staple driver positioned in the head for upward and downward movement, a lever extending longitudinally of the head and pivoted at its rear end to the same and pivotally connected at its front end to the staple driver, a work striker located below said lever and pivoted intermediate of its ends to the head and having a projecting nose movable upwardly by impact with the work, and a link pivoted to the work striker in rear of the pivot thereof and to the said lever intermediate of the ends thereof, whereby the driver and the lever will be moved downwardly by impact of the striker with the work.

6. A stapling implement including a head, a staple driver positioned in the head for upward and downward movement, a lever extending longitudinally of the head and having spaced sides pivoted at their rear ends to the head at

opposite sides thereof and pivotally connected at their front ends to the staple driver, a work striker located below the lever and pivoted intermediate of its ends to said head and having spaced sides located at opposite sides of the head, said striker having a projecting nose movable upwardly by impact with the work, and links pivotally connected with the rear portions of the sides of the striker and to the sides of the lever intermediate of the ends thereof whereby the lever and the driver will be moved downwardly by said impact of the striker with the work.

7. A stapling implement comprising a handle provided with a guideway for processional advance of staples therethrough, a head at one end of the handle composed of two parts separated to provide between them a continuation of the staple guideway, means connecting the two head parts as a unit, a staple driver positioned in the head for upward and downward movement, a lever extending longitudinally of the head and pivoted at its rear end to the same and at its front end to the staple driver, a work striker pivoted intermediate of its ends to the head and having a projecting nose portion movable upwardly by impact with the work, and a link pivoted to the rear portion of the work striker and to the lever intermediate the ends thereof whereby the lever and driver will be moved downwardly by the said impact of the striker with the work.

8. A stapling implement comprising a handle provided with a longitudinal guideway for processional advance of staples therethrough, a head affixed to the handle at the front end thereof and formed with a staple guideway in continuation of that of the handle, said head being provided with a forwardly extending ledge, a staple driver positioned in the head for upward and downward movement forwardly of the ledge, a lever extending longitudinally of the head and pivoted at its rear end to the same and at its front end to the driver, a work striker pivoted intermediate of its ends to the head and having a projecting nose movable upwardly by impact with the work, a link connecting the rear portion of the striker with the lever, whereby the lever and the driver are moved downwardly by said impact of the driver with the work, and a spring seated upon said ledge and arranged to urge the lever and the staple driver upwardly.

9. A stapling implement comprising a handle having a longitudinal guideway for processional advance of staples therethrough, a head attached to the handle at the front end thereof and composed of upper and lower blocks and connecting side plates, the upper block terminating at a point spaced from the proximate end of the handle to provide a chamber open at the top, a staple driver positioned in the head for upward and downward movement, a lever extending longitudinally of the head and pivoted at its rear end to the same and at its front end to the staple driver, a work striker pivoted intermediate of its ends to the head and having a front projecting portion movable upwardly by impact with the work, a link connecting the rear portion of the work striker with the lever, and a spring arranged within said chamber and seated upon the head and arranged to urge the lever and the driver upwardly.

10. A stapling implement comprising a handle, a core bar located within the handle and arranged to support staples, said bar being provided at its front end with a head wall extending outwardly and upwardly therefrom, a head having

side plates provided with outturned flanges abutting the head wall of the core bore, means for detachably connecting the head wall and said flanges, a staple driver positioned in the head for upward and downward movement, a lever extending longitudinally of the head and pivoted at its rear end to the same and at its front end to the staple driver, a work striker pivoted intermediate of its ends to said head and having a projecting nose movable upwardly by impact with the work, and a link connecting the rear portion of the work striker with the lever for moving the lever and the driver downwardly when the nose of the work striker is moved upwardly.

11. A stapling implement comprising a casing, a staple driver mounted within the casing for upward and downward movement and composed of a blade and a weighted head provided at its opposite sides with flanges having laterally projecting trunnions and receiving the blade between the flanges, means for securing the blade to the weighted head, a lever extending longitudinally of the casing and composed of spaced sides pivoted at their rear ends within the casing and provided

5
10

at their front ends with slots receiving the said trunnions, a work striker pivoted intermediate of its ends within the casing and having a front projecting nose portion movable upwardly by impact with the work and a link connecting the rear portion of the work striker with said lever for moving the lever and the staple driver downwardly when the nose of the striker is moved upwardly with respect to the casing.
